STITCH-DOWN SHOE STRUCTURE

Isidor Hoffenberg, Milford, Conn.

Application February 21, 1939, Serial No. 257,709

2 Claims. (Cl. 36—16)

The present invention relates to stitchdown shoe structure or construction and more particularly to improvements in the construction of the heel portion of such a shoe enabling a close edge heel seat method of manufacture which can be carried out much faster than the regulation method.

In making stitchdown shoes of the usual type, the leather of the upper is lasted with a fold near its edge at the bottom of the last so as to provide an edge portion which projects outwardly from the fold. The insole is positioned on the bottom of the last and the upper adjacent to the fold is secured to the insole by any suitable means such as stitching leaving the edge portion of the upper overlying the insole. After placing a welt piece in position above the edge portion of the upper to add to the appearance and strength of the shoe, the outsole is secured in position by a line of outsole stitching passing through the welt, the upper, the insole and the outsole. This method of manufacture produces a shoe in which the outsole stitching is visible around the heel portion of the shoe as well as around the edge of the sole to the front of the heel, the heel projecting at the sides and rear of the heel portion of the upper part of the shoe.

An important object of the invention is to provide a novel stitchdown shoe of improved construction and appearance. Another object of the invention is to provide improved structure for the heel portion of the stitchdown shoe.

According to a preferred manner of carrying out the invention, there is provided between the heel portion of the insole and the last a heel piece or "dutchman" as it is known in the trade, and this heel piece may be beveled or undercut so as to allow the lining, counter and upper to be wiped in folded form in and under the bevel of the heel piece or "dutchman" and the stitching of these parts to the insole to be effected so as to urge the folded material under the edge of the heel piece. The outside stitching around the heel can then be effected through a usual welt and close to the upper and will be hidden in the finished shoe so that projection of the edge of the heel from the shoe may be avoided so that when the heel of the shoe is made in this way the shoe has in general the appearance of a "Goodyear welt" shoe of much higher grade.

Heretofore it has been proposed to construct the front part of the shoe by the ordinary stitchdown method and at the rear of the shoe to narrow the insole and bring the upper around the edge to the bottom of the insole and secure it

thereto preparatory to securing the heel in position. It will be evident that according to applicant's method the stitching can be carried completely around the margin of the shoe and attachment effected in a single operation, whereas, if the heel portion of the upper is secured to the insole in some other way, two different kinds of operation may be necessary, one for the front part of the shoe and the other for the heel portion of the shoe, and the cost of manufacture would be much higher.

Other objects, features and advantages will appear upon consideration of the following detailed description of the drawing in which:

Fig. 1 is a side view of a shoe embodying the present invention, the shoe being cut away at the heel to show the attachment of the insole and outsole to the upper, the counter and the lining.

Fig. 2 is a view in perspective of a heel piece formed according to the present invention with an undercut edge and a front end tapered to gradually reduce the thickness;

Fig. 3 is a rear elevation of a shoe partly in section along the line 3—3 of Fig. 1;

Fig. 4 is a section showing a heel piece of the present invention resting on the upper surface of an insole; and

Fig. 5 is a section taken along the line 5—5 of Fig. 1.

Referring to the drawing there is illustrated a stitchdown shoe 10 embodying the present invention and comprising an upper 11, a lining 12, an insole 13, an outsole 14, a heel-stiffener or counter 15, a welt 16 and a heel piece or "dutchman" 17 formed according to the present invention with an undercut edge at the sides and rear and a forward end so tapered as to decrease in thickness toward its forward edge.

In making the shoe 10, the upper 11, the lining 12 and the counter 15 are assembled and placed on a last (not shown) and the insole 13 and the heel piece of "dutchman" 17 are placed on the bottom of the last with the heel piece between the last and the insole as suggested by Figs. 1, 3 and 4.

The parts are so assembled that the material of the upper and the lining are folded and parts thereof extend outwardly over the top of the insole 13. Around the shank and the front of the sole, the lining 12 as well as the upper 11 will extend outwardly for attachment to the insole and around the heel portion of the shoe not only the upper and the lining but also the lower edge of the counter will extend outwardly over

the upper surface of the edge portion of the insole.

After all the parts of the shoe have been assembled on the last, a line of insole stitching 19 may be run completely around the shoe to secure the outwardly folded parts to the insole. Along the shank and front part of the shoe the result will, as indicated in Fig. 5, be substantially the same as in standard stitchdown shoes. However, around the heel portion of the shoe, a different result may be obtained due to the use of the heel piece 17 with the undercut edge at the sides and rear and the tapered forward end. Due to the undercut edge of the heel piece the insole stitching 19 may be inclined and applied so as to draw the lining, counter and upper inwardly with reference to the shoe and act to force them under the overhang caused by undercutting the edge of the heel piece. This will render the upper 20 part of stitching 19 substantially invisible. Then the welt 16 is placed in position and the outsole stitching 20 is run around the edge of the sole, the part of the stitching at the heel being inclined. It will be evident that in forming both insole and 25 outsole stitching in inclined position at the heel, the parts of the machine tends to bend the edge portion of the sole away from the shoe and that, when the pressure of the shoe against the machine is released, the sole will tend to return to its 30 flat form and carry the stitching inwardly toward the shoe to hide it or render it less conspicuous. After the outsole 14 has been stitched, a heel 21 may be formed on the shoe.

The welt may be provided with a longitudinally 35 extending cut or scoring in the upper face thereof. The outsole stitching tends to bury itself in the cut or groove and deformation of the welt in the finishing operation also tends to hide the outsole stitching at the heel.

Another important advantage of the present 40 invention is that the undercut edges act on the heel portion of the upper, including the counter and tend to hold the counter and associated parts in position.

It should be understood that certain features 45 may be varied and that certain features may be used without others, without departing from the true scope and spirit of the invention.

What I claim is:

1. A stitchdown shoe with a close edge heel seat, comprising an insole, a heel piece over the heel portion of said insole, said heel piece being undercut at its sides and rear and tapered downwardly to a thin front edge, an upper outturned at its entire lower margin, a counter in the heel portion of said upper and having its lower edge outturned, insole stitching connecting to the insole the outturned portion of the counter and the 10 outturned portion of the upper at its entire lower margin, the insole stitching around the heel portion of the insole being inclined inwardly and downwardly to draw the upper and counter toward the space beneath the undercut edge of the 15 heel piece, a welt over the outturned portion of said upper, an outsole, and a line of outsole stitching passing through the welt and extending completely around the shoe, the portion of the outsole 20 stitching around the heel of the shoe being inclined and close to the shoe to draw the welt inwardly and conceal the stitching.

2. A stitchdown shoe with a close edge heel seat, comprising an insole, a heel piece over the heel portion of said insole, said heel piece being undercut at its sides and rear and tapered downwardly to a thin front edge, an upper with a lining both folded to provide outturned portions around their entire lower margins, a counter in the heel portion of said upper and having its 25 lower edge outturned, insole stitching connecting to the insole the outturned portions of the counter and the lining and the outturned portion of the upper at its entire lower margin, the insole stitching around the heel portion of the insole being 30 inclined inwardly and downwardly to draw the upper, the lining and the counter toward the space beneath the undercut edge of the heel piece, a grooved welt over the outturned portion of said upper, an outsole, and a line of outsole 35 stitching passing the rough said welt and extending completely around the shoe, the portion of the outsole stitching around the heel of the shoe being inclined and close to the shoe to draw the welt inwardly and conceal the stitching.

ISIDOR HOFFENBERG.
